CHAINING PRESSER FOOT FOR FELLING MACHINES

Filed Oct. 23, 1926

By Stewart & Mason

Attorneys

UNITED STATES PATENT OFFICE.

JOHN M. BIDDLE, OF CHICAGO, ILLINOIS, ASSIGNOR TO UNION SPECIAL MACHINE COMPANY, OF CHICAGO, ILLINOIS, A CORPORATION OF ILLINOIS.

CHAINING PRESSER FOOT FOR FELLING MACHINES.

Application filed October 23, 1926. Serial No. 143,648.

The invention relates to new and useful improvements in a chaining presser foot for felling machines, and more particularly to a chaining presser foot of the type shown in the application filed by Joseph Berger, July 9, 1926, Serial No. 121,425. In this prior application, the foot portion of the presser foot is provided with a channel extending lengthwise thereof for guiding the fabric sections for felling, and located in this channel are chaining fingers which are pivoted to the foot adjacent the rear end thereof, and which chaining fingers terminate at the needle holes in the foot. These chaining fingers are yieldingly 15 pressed downwardly at their free ends by the aid of springs.

An object of the present invention is to provide a chaining foot of the above type, wherein the enchain thread loops are engaged by 20 a yieldable chaining finger rigidly secured to the foot portion and disposed in the channel which guides the fabric sections during felling.

A further object of the invention is to provide a chaining presser foot of the above type, wherein the yieldable finger is so shaped that the free end thereof is limited in its movement in a downward direction by the engagement of the free end of the yieldable finger 25 with the upper face of the presser foot.

These and other objects will in part be obvious, and will in part be hereinafter more fully disclosed.

In the drawings which show by way of 30 illustration one embodiment of the invention—

Figure 1 is a side view of a presser foot embodying the improvements, with the needles indicated in broken lines;

Fig. 2 is a plan view of the presser foot;

Fig. 3 is a longitudinal sectional view through the presser foot;

Fig. 4 is a sectional view on the line 4—4 of Fig. 2;

Fig. 5 is a perspective view of the spring member which forms the yielding chaining fingers, and

Fig. 6 is a plan view of a portion of the throat plate with which the presser foot is 50 used.

The presser foot is particularly designed for felling, and is of a character similar to

that shown in the application filed by Joseph Berger, above referred to. The presser foot as indicated in the drawings, consists of a 55 supporting shank 1 adapted to be attached to the presser bar 2 by a clamping collar 3 with which is associated a clamping screw 4. The foot portion 5 is pivoted to the shank 1 by a pivot bar 6 so that the foot portion is capable 60 of rocking on its pivot bar. This greatly aids in the passing of the fabric beneath the presser foot and in the crossing of seams. This presser foot portion 5 is provided with a channel 7 extending the full length of the 65 presser foot, and in fact, preferably extending up the under face of the turned up toe 8 of the foot portion. This channel is of substantially the width of the fold in the fabric sections to form the felled seam. In Fig. 4, 70 I have shown a sectional view through the presser foot, and the fabric sections S and S' interfolded to form the felled seam F, and it will be noted that these interfolded portions of the fabric sections lie in the channel 75 7, and this channel becomes a guide for the felled seam. The presser foot is particularly adapted for use in connection with a two-needle machine having two needles 9 and 10. These two needles pass through needle openings 11 and 12 in the presser foot, and needle holes 13 and 14 in the throat plate, indicated 80 at 15 in Fig. 6 of the drawings. The needles will penetrate the interfolded sections of the fabric at each side of the felled seam, and thus 85 the fabric sections are joined by two parallel lines of stitching.

The invention is directed particularly to the chaining fingers which are used in connection with this type of presser foot. The 90 foot portion 5 is also provided with a recess 16 in the inclined rear face thereof, and in this recess, is located a plate 17 of spring metal. This plate is of substantially the same width as the recess 16, and a screw 18 passing 95 through an opening 19 in the plate, firmly secures the plate to the presser foot. This plate 17 is split at 20 so as to form two chaining fingers 21 and 22. Two chaining fingers are shown in the present embodiment of the 100 invention, as two needles are used. If it was a single needle machine, then there would be only the one chaining finger, and if more needles are used, then there would be the same

number of chaining fingers as there are needles.

These chaining fingers are located in the channel 7 in the under face of the presser foot. The presser foot is provided with an opening 23 in rear of the needle hole 12. This opening extends up through the presser foot, and the chaining finger is bent so as to extend up through the opening 23, and it is then 10 bent horizontally so as to overlie the upper surface of the presser foot. The extreme front end of the overlying part of the finger 21 is provided with a recess 24 which conforms to the needle hole 12. The throat plate 15 is provided with a solid section 25 directly in rear of the needle hole 14. The throat plate has feed slots 26, 26, 26, and also feed slots 27, 27. The chaining finger 22 is likewise bent upwardly and extends up through an opening 28 through the presser foot and overlies the top of the presser foot directly in rear of the needle hole 11. Said chaining finger 22 is also cut away at 29 to conform to the needle hole. The throat plate is provided with a 20 solid section 30 directly in rear of the needle hole 13.

The channel fingers being made of spring metal are shaped so that they normally spring downwardly at their free ends, and the downward movement of each chaining finger is limited by an overhanging portion which engages the upper face of the foot. In other words, if the presser foot is raised slightly at one side of the felled seam for any reason, the 30 chaining finger at the other side will move down so as to engage the material. These chaining fingers yield also to the interfolded sections of the fabric, so that the side walls of the channel 7 become guiding walls for 40 directing the seam. The chaining fingers at the rear end of the bottom surface of the foot are substantially flush with the foot, and the front end of the fingers move to a point above the lower face of the foot to form the guiding 45 channel, or to a position slightly beneath the lower surface of the foot.

The real function of these chaining fingers is to engage the enchain loops passing over the solid sections directly in rear of the needle holes in the throat plate. The pressure of the spring chaining fingers against the enchain loops so that perfect stitches are 50 formed, even though there is no fabric in the machine to anchor and hold the enchain loops. In other words, these fingers clamp the enchain loops and hold the same to the same extent that the threads are held when 55 anchored in the material. As a result, between stitched articles, a perfect rope of enchain loops is formed, and there is no liability of skipping of stitches between articles. One article is passed through and 60 out of the machine, and then a series of en-

chain loops are formed, and then the next article passes underneath the presser foot and is stitched. The operator does not necessarily have to stop the machine to cut the threads, and does not have to pull on the stitched article as it leaves the machine in order to insure chaining, and therefore, the operator is free to direct the next article underneath the foot. The presser foot, of course, rocks on its pivotal support as it passes on to and off 75 from the stitched articles in the usual manner.

It is obvious that minor changes in the details of construction and the arrangement of the parts may be made without departing from the spirit of the invention as set forth 80 in the appended claims.

Having thus described the invention, what I claim as new and desire to secure by Letters-Patent, is—

1. A presser foot for sewing machines 85 comprising a foot portion having a needle hole and a channel extending lengthwise thereof for guiding the fabric sections for felling, a yielding chaining finger located in said channel, said finger being fixed to the 90 foot portion at the rear end thereof and free at its front end, said finger terminating in rear of and at the needle hole in the foot, and having means for limiting the downward movement of said finger, the front end of said 95 finger being adapted to engage and clamp the enchain loops at a point directly in rear of the needle hole.

2. A presser foot for sewing machines 100 comprising a foot portion having a channel extending lengthwise thereof for guiding the fabric sections for felling, a yielding chaining finger located in said channel, means for rigidly securing said finger to the presser foot at the rear end thereof, said presser foot having a needle hole and an opening therethrough in rear of the needle hole, said yielding chaining finger being bent upwardly and extending up through the opening in rear 105 of the needle hole and overlying said presser foot, whereby the downward movement of the free end of the chaining finger is limited, said chaining finger at the forward end thereof being adapted to engage a solid portion of the throat plate for holding the enchain loops during chaining off.

3. A presser foot for sewing machines comprising a foot portion having a channel extending lengthwise thereof for guiding the fabric sections for felling, said foot portion having an upturned rear end with a recess in its under face, and having a plurality of needle openings through which the needles pass, said foot portion having openings therethrough in rear of the needle openings, a plate 115 of spring metal located in the recess at the rear of the foot and secured therein by a clamping screw, said plate being formed into independent chaining fingers located in said channel in the under face of the foot and 120

bent upwardly at their free ends to pass up through the openings in rear of the needle holes, the extreme forward ends of said fingers being bent so as to overlie the presser foot and limit the downward movement of said fingers, said chaining fingers at their free forward ends being adapted to engage

the enchain thread loops and press the same against the solid portions of the throat plate in rear of the needle holes in the throat plate during chaining off. 10

In testimony whereof, I affix my signature.

JOHN M. BIDDLE.
